ROLLER SKATE

Grant L. Fuller, Cleveland Heights, Ohio

Application August 22, 1944, Serial No. 550,497

2 Claims. (Cl. 280—11.28)

1

This invention relates, as indicated, to roller skates, but has reference more particularly to the foot plate or hanger supporting structure of the skate.

A primary object of the invention is to provide a skate of the character described in which the tilting movement of the foot plate relatively to the supporting structure is so controlled as to permit increased maneuverability without danger of the skater falling or of damage or distortion to the skates.

Another object of the invention is to provide skates which have incorporated therein structure permitting an improved action in free-style skating.

A further object of the invention is to provide a skate of reduced overall width.

Other objects and advantages of the invention will be apparent during the course of the following description.

In the accompanying drawings, forming a part of this specification, and in which like numerals are employed to designate like parts throughout the same.

Fig. 1 is a plan view, partially broken away, of a skate embodying my invention;

Fig. 2 is a side elevation of the skate, with the rear portion thereof in longitudinal cross-section;

Fig. 3 is a front elevation of the skate, with one of the rollers and associated elements in cross-section, and

Fig. 4 is a fragmentary cross-sectional view, taken on the line 4—4 of Fig. 2.

Referring more particularly to the drawing, the skate will be seen to comprise a foot plate 1 having a toe plate portion 1a and a heel plate portion 1b.

Secured to the aforesaid toe and heel plate portions, as by means of rivets 2, are hangers 3, each of which is formed to provide a downwardly extending inclined socket portion 3a and a downwardly extending inclined pivot or thrust member 3b, the lower end of which is smoothly rounded. The member 3b of each hanger is inclined in an opposite direction to the socket 3a of that hanger, but the sockets and thrust members of each hanger are inclined oppositely to the corresponding socket and element of the other member.

The skate further includes trucks 4, each of which comprises an axle portion 5 in the form of a transversely extending tubular structure in which an axle or spindle 6 is mounted and secured against rotation as by means of a pin 7

2

(Fig. 2). Extending vertically upward from the axle portion 5 of each truck is an arm 8, which is formed integrally with such axle portion, and the upper end of which is recessed as at 9 for the reception of a socket element 10, the element 10 being preferably made of a wear-resisting steel and being secured in such recess by a pressed fit. The socket element 10 is recessed to provide a smoothly rounded seat or thrust surface for the pivot member 3b. The lower end of the member 3b is preferably of hemispherical form, and the thrust surface of the socket element 10 is likewise of hemispherical form, so as to provide, in effect, a ball and socket joint between these parts, permitting substantially universal movement of the truck relatively to the hanger. The upper portion of the wall of the recess in the socket element 10 is flared to permit such universal movement.

20 Each of the trucks further includes, as an integral part thereof, a second arm 11, which is of circular form, the axis of which is substantially in alignment with the axis of the socket portion 3a of the hanger 3. The arm 11 is provided with an elongated opening or slot 12, the walls of which are flared for a purpose to be presently described, and is further provided with an annular flange 13. The arm 11 forms a seat for a cushioning element, such as a block of rubber 14, the base of which is confined by the flange 13. The rubber block 14 is of conical form and has secured to its upper or smaller end thereof, preferably as by vulcanization, a second block of rubber 15, of cylindrical form and of substantially the same diameter as the upper end of the block 14, the block 15 being preferably made from a grade of rubber which is harder or less resiliant than that from which the block 14 is formed. The upper end of the block 15 is confined within an inverted metallic retaining cap or cup 16, between which and the lower end of the socket 3a a nut 17 is interposed.

The nut 17 is in threaded engagement with a screw 18, which extends through the slot 12 and axially through the rubber blocks 14 and 15, the cap 16, and the socket 3a, the screw being also in threaded engagement with the socket 3a, which is internally-threaded for this purpose.

25 A washer 19 is interposed between the head of the screw 18 and the lower surface of the arm 11.

The skate further includes a frame bar 20 having upturned ends 21 which are interposed between the head of the nuts 17 and the retainer caps 16, the nuts 17 having reduced lower por-

tions 22 which extend into openings of the same size in the ends 21 of the frame bar.

The pressure exerted upon the cushioning blocks 14 and 15, and therefore the resiliency of these blocks may be regulated by adjusting the screws 18, the nuts 17 being utilized as locking nuts to lock the screws in adjusted positions. In order to prevent portions of the blocks 14 from being squeezed into the slots 12 incidental to such adjustment, a fiber disc or washer 23 of a diameter greater than the width of the slots 12 may be molded or otherwise secured to the lower faces of the blocks 14 adjacent the openings in these blocks, the blocks being recessed adjacent the openings for receiving the discs.

It will be apparent from the foregoing description that both arms of each truck are pivotally connected to rigid portions of the skate, the arms 8 being pivotally connected to the pivot members 3b and the screws 18 being pivotally movable relatively to the arm 11, the flared walls of the slots 12 permitting such movement. The washers 19 serve as fulcrums for the heads of the screws 18 incidental to such pivotal movement.

Due to the aforesaid pivotal connections, the foot plate and other portions of the skate which are rigidly connected to the foot plate may tilt in all directions relatively to the trucks, this tilting movement being resisted and controlled by the rubber blocks 14 and 15. Due to the conical shape of the block 14 and the fact that this block is exposed or unconfined for substantially its entire length, the resistance to the aforesaid tilting increases in substantially direct proportion to the distance along the block 14 from the foot plate, a condition which has been found to be highly desirable, particularly because it provides a greatly improved "action" for so-called "free-style" skating. In other words, the skate permits increased maneuverability for the skater, enabling the skater to execute more difficult and complex movements, without danger of spilling or damage to the skates.

It may be noted that the slot 12 is longer than is found in present-day skates of this type, and that the area of the base of the rubber blocks 14 is considerably greater than the area of cushioning blocks found in such skates. These factors tend to reduce to a minimum the hazard of the upper end of the slot being forced against the screw 18. In skates of a similar type which are now in use, the screw 18 is frequently bent, due to the fact that free-style skaters, requiring more rubber resistance than is presently provided, will tighten the adjusting screw 18 to such an extent as to bring the ends of the slots through which the screw extends into contact with the screw, creating a condition wherein the shock of a jump will cause the screw to bend or break, or even cause some other part of the skate to give way. The use of hard and unyielding rubber blocks, in an attempt to prevent the slot ends from touching the screw, has been tried by thousands of skaters, and has been discarded, because such an expedient not only eliminates the natural vertical cushioning effect of the rubber, but greatly reduces also the sidewise tilting effect, thereby causing a slipping of the wheels on turns. The present invention retains the desirable cushion-

ing effect, while eliminating the hazard of the screw-slot end contact.

As a further refinement, and in order to decrease the overall width of the skate as far as possible, the axles or spindles 6 are not extended entirely through the rollers 24, but terminate short of the outboard faces 25 of the rollers, as shown in Fig. 3. The ends of the axles are internally threaded for the reception of socket-head screws 26, the heads of which bear against bearing-retaining washers 27, and project to only a slight extent beyond the aforesaid outboard faces 25. In this way, the overall width of the skate is considerably reduced.

It is to be understood that the form of my invention, herewith shown and described, is to be taken as a preferred example of the same, and that various changes in the shape, size and arrangement of parts may be resorted to, without departing from the spirit of my invention, or the scope of the subjoined claims.

Having thus described my invention, I claim:

1. In a roller skate of the character described, a foot plate; a truck supporting said foot plate, said foot plate being tiltable relative to the truck; and a resilient, rubber-like member interposed between the truck and foot plate for normally positioning said foot plate in a plane at a given angle relative to the truck, said member being supported at opposite ends by relatively rigid members, said member being in the form of a conical section intermediate said members, and the base of said member being supported by said truck whereby resistance to tilting of said foot plate from said angle relative to the truck increases as the degree of such tilting increases.

2. In a roller skate of the character described, a foot plate; a truck supporting said foot plate; a resilient, rubber-like member interposed between the truck and foot plate, said member having an opening extending therethrough; a plate for receiving an end surface of said member, said plate having an opening in alignment with said opening through said member; means for retaining said member in position including a shaft extending through said opening through said member, said member having a recessed area in said end surface, said opening through the member opening into said recessed area; and a relatively rigid member disposed in said recessed area, said rigid member having an opening therethrough in alignment with the opening through said resilient member.
